By A. S. Johnson
his Attorney.

UNITED STATES PATENT OFFICE.

EDWARD R. KOTTKE, OF ST. PAUL, MINNESOTA, ASSIGNOR OF ONE-THIRD TO H. T. KURRASCH, OF ST. PAUL, MINNESOTA.

GAGE-COCK.

1,322,797.

Specification of Letters Patent. Patented Nov. 25, 1919.

Application filed March 6, 1919. Serial No. 280,915.

To all whom it may concern:

Be it known that I, EDWARD R. KOTTKE, a citizen of the United States, residing at St. Paul, in the county of Ramsey and State of Minnesota, have invented certain new and useful Improvements in Gage-Cocks, of which the following is a specification.

This invention relates to gage cocks and more particularly to the types commonly used on locomotive boilers for ascertaining the level of the water therein.

An object of the invention is to provide a gage cock, the interior of which is not open to incrustation except when its valve is unseated.

A further object of the invention is to provide a device that may be removed from the boiler without disturbing the insulation, customarily covering the outside of the boiler wall.

A still further object of the invention is to provide a gage cock so constructed as to be comparatively safe against accidents.

Referring to drawings:

25 Fig. 1, is a side view of the invention as applied to the vertical wall of a boiler.

Fig. 2, is a longitudinal sectional view of the invention the valve stem being shown in full.

30 Fig. 3, is a sectional view on line 3—3 of Fig. 2.

Fig. 4, a sectional view on line 4—4 of Fig. 2, and

35 Fig. 5, is a sectional view of an old style gage cock.

In the drawings 1, is the valve stem, formed at its inner extremity with a valve 2, seated on the conic seat 3 in the inner end of the casing 4. The casing comprises a shank portion 5, tapered inwardly, an integral ring or collar 6, circular in cross section and of greater diameter than the shank portion and located at the top thereof, an annular chamber 7 located above said ring, 40 and a screw-threaded neck 8. The casing is bored longitudinally throughout its length to rotatably receive the valve stem 1, which latter is of uniform diameter snugly fitting said bore, and projects through the outer end 45 of the casing. The portion of the stem outside the casing is formed with a left handed thread 9, which fits a thread in the packing nut 10, the nut suitably screw-threaded to fit over the thread on the neck 8. The thread 50 on the neck is cut right handed or opposed

in direction to that of the stem, for the purpose of preventing confusion among operatives who have been accustomed to handling the old form of gage cocks designed to be turned to the right in seating the valve.

60

As illustrated in Fig. 5, the inner end of the stem of old style cocks was simply tapered to constitute a valve, which had a seat in the chamber corresponding to chamber 7.

65

To avoid the necessity of a large and cumbersome casing, the stem is of ordinary size and simply chamfered. To secure therefore, suitable surface, the bore beyond the stem, in open communication with the interior of the boiler must of necessity be very small.

70

The disadvantage of so small a bore will hereinafter be dwelt upon. The stem 1, is provided with a hand wheel 11, secured to the outer end thereof and formed with a plurality of longitudinal grooves or ports 12,

75

circumferentially spaced and extending to the base of the neck 8. When the stem is turned to the left, the valve 2 is unseated and the steam or water, as the case may be, will traverse the ports 12 and enter the chamber 7 to escape therefrom through the spigot 13 which latter communicates with the chamber.

80

Extending from the lower face of the ring 6 to the end of the shank portion 5, and closely fitting around the latter, is the tapered nipple or sleeve 14, having screw-threaded ends 15. The lower end is adapted to be screwed into the wall 16 of the boiler,

85

the nipple being of sufficient length to extend through the asbestos covering, not shown, over the outer surface of the boiler. The nipple is permanently secured in position on the boiler; the casing 4, being held in position by the holding nut 17, the latter fitting

90

over the ring 6 and having threaded connection with the nipple.

95

Referring again to Fig. 5, it will be noted, that the entire cock must be removed from the boiler, when it is desired to repair the cock, thus tearing up the asbestos insulation. Further, removal of the cock requires each time, recutting of the threads on the cock because of mutilation of same, as it is usually made of brass.

100

The duct beyond the stem owing to its small size, soon fills with lime, due to incrustation, because it is at all times filled with water, whereas in applicant's device, water enters the ducts only when the valve is opened.

105

110

When it is desired to remove the device from the boiler, the nut 17 is disengaged from the nipple 14, and the casing withdrawn. It has been found, that the shank 5 is much more readily removed from the nipple, when the shank is tapered, because of the tendency to stick, due to the deposit of lime which may find its way into the joint. The hexagonal section 18 is provided 10 to be gripped for the purpose.

I claim:

A gage cock, comprising a tubular body of uniform bore having at its inner end a valve seat and at its opposite end a threaded 15 neck portion, a valve for said seat, a fluted stem on said valve rotatably fitting said bore, said flutes constituting ports, said stem extending beyond said body and having a hand wheel at its outer extremity, a chamber having 20 an outlet surrounding said fluted stem adjacent and below said neck portion, a

thread on said stem extension opposite in direction to the thread on said neck portion, a nut fitting at its respective ends the thread of the stem and neck portion, a collar on 25 said body below said chamber, the body between said collar and valve seat frusto-conical in form, a sleeve threaded on each of its ends fitting over said frusto-conical portion of the body and extending from said 30 seat to said collar and against the latter, and a connecting nut surrounding said body and fitting from above over said collar, the threads of said nut engaging the threads of 35 said sleeve to hold said body positioned in the sleeve.

In testimony whereof I affix my signature in presence of a witness.

EDWARD R. KOTTKE.

Witness:

GEORGE VOELKER.
